UNITED STATES PATENT OFFICE

2,398,940

SURGICAL HEADREST

Samuel R. Jones, Los Angeles, Calif.

Application October 19, 1942, Serial No. 462,584

3 Claims. (Cl. 128—1)

My invention relates in general to hospital equipment, and relates in particular to an adjustable rest for supporting the human head during operative procedure or superficial treatment.

It is an object of the invention to provide a head rest having cushioned portions to receive the frontal and anterolateral portions of the face of a person in supine position, whereby the parietal, occipital, and posterior temporal portions of the head will be supported in exposed position.

It is also an object of the invention to provide a surgical head rest of the character described in the foregoing paragraph in which the rests for engagement with the head are readily adjustable in spatial arrangement.

It is a further object to provide a surgical head rest wherein the head supporting parts of the rest are angularly adjustable so as to be tiltable in forward-rearward direction, and also laterally, with means for rigidly supporting the parts in tilted adjustment.

A further object of the invention is to provide a surgical head rest wherein the head supporting parts are vertically adjustable.

Although the invention is of especial utility for supporting the head in face downward position, its parts may be readily adjusted so as to support the occipital-parietal portions of the head, with the face exposed. Also, it is a feature of the invention to provide the head rest device with means for receiving binding members whereby the head may be stabilized so as to prohibit movement thereof during an operation.

Further objects and advantages of the invention will be brought out in the following part of the specification.

Referring to the drawing which is for illustrative purposes only:

Fig. 1 is an elevational view of a preferred embodiment of my invention showing the manner of its use.

Fig. 2 is a partly sectioned plan view of the head rest shown in Fig. 1.

Fig. 3 is an enlarged cross-section taken as indicated by the line 3—3 of Fig. 2, this view showing the head supporting parts of the head rest in laterally sloping position.

Fig. 4 is an enlarged fragmentary cross-section taken on a plane represented by the line 4—4 of Fig. 3.

The head rest comprises a base 10 and a cushioned rest 11. The base 10 consists of a tube 12 bent to U-shape form, and a pair of posts 13 extending upward from the intermediate portions of the side parts or legs 14 of the U-shape base

10. The tube 12 has means to support the same in raised relation with respect to a supporting surface 15, these means preferably consisting of rubber rings 16 surrounding the tube 12 in spaced positions.

In the center of the rounded portion of the base 10 there is an upwardly projecting perforated lug 17 to receive a screw 18. The vertical posts 13 are tubular, and near the upper ends thereof are provided with drilled and threaded bodies 19 to receive screws 20 for engagement with openings 21 in vertically arranged tubular bars 22 which are slideable in the posts 13.

The rest 11 comprises a U-shaped member 23 having substantially symmetrical parts 24 articulated on a substantially vertical hinge axis 25 formed by a hinge 26 which is secured to the adjacent ends of the symmetrical parts 24. As shown in Fig. 2, the side parts 24 are continuously curved, the extremities 27 thereof being of lesser curvature than the portions adjacent the hinge 26. The side members 24 of the rest are cushioned, this being accomplished preferably by surrounding the same with walls 28 of sponge rubber which may be covered with fabric, 50.

Levers 29 are extended rearward from the hinge portions of the side members 24 as shown in Fig. 2, and means 30 are provided to move the extremities of these levers 29 together or apart so as to swing the members 24 on the hinge axis 25 so as to change the spatial relation of the side portions of the rest 11 in accordance with the size of the face or cranial part of the head which is to be supported thereon. The levers 29 comprise short sections of metal tubing brazed or welded to the parts 24. Screws 31 extend vertically through the outer portions of these levers, and engage eyes 33 on the ends of screws 34 of a turn buckle mechanism 35 comprising the adjusting means operative between the extremities of the levers 29.

In a vertical transverse plane defined by the posts 13, inner legs 30' project downward from the medial portions of the metal members 24. These members 30' are tangential to circles lying within and smaller than the circles defined by the cross sectional areas of the sponge rubber walls 28, as shown in Fig. 3. Therefore, no portion of the head of a patient supported by the rest 11 will engage the metal parts 30'. Spaced from these legs 30' there are outer legs 31', and each pair of legs comprising a leg 30' and a leg 31' supporting a transverse bar 32. These bars 32 extend through vertically elongated slots 33' in the upper ends of the tubes 22, and are slid-

able in these slots 33' as the adjustment means 30 is actuated to move the side members 24 together or apart, or as the rest 11 is tilted at an angle, as shown in Fig. 3. The legs 30' and 31' are formed from a continuous piece of flat metal bent to approximately U-shaped form.

The invention also provides means for tilting the head rest 11 relatively to a longitudinal axis or a lateral axis, or both. This means comprises a pair of turn buckles 34', the lower ends 35' of which are connected by the screw 18 to the lug 17, and the upper ends 36 of which are respectively connected by straps 37 and screws 38 to the rearward projections or levers 29. When the turn buckles 34' are simultaneously operated in a like manner, the far end of the rest 11 will be raised or lowered by rotation of the rest on the axis defined by the transverse pins 32. When the turn buckles 34 are operated in an unlike manner, so that the effective length of one will be greater than the effective length of the other, as shown in Fig. 3, the rest 11 will be tilted laterally. The post extensions or bars 22 will be raised and lowered in accordance with the adjustment of the rest 11.

The invention also provides means to lock the rest against lateral movement, such means comprising, as shown in Figs. 1 and 4, a bar 39 secured at 40 within one of the tubular members 22, this bar 39 extending adjacent a side of a cross pin 32 so as to be clampable against this member 32 by a screw 41. When this locking means is actuated by tightening down the screw 41, the transverse bar 32 is prevented from sliding back and forth through the slot 33' receiving the bar 32.

It is possible to adjust the rest 11 to a considerably greater angle to horizontal than shown in Fig. 3. Also, the patient's head may be immobilized relatively to the rest by use of long bands or strips which are passed under the side portions or legs of the base 10 and carried across a portion of the patient's head, with sufficient tension to maintain the head tightly in contact with the rest 11; when the patient is in face-down position, the nose and mouth are both exposed, making it possible to administer an anesthetic. Also, the head is held in raised position so as to provide space for a receptacle.

I claim as my invention:

1. In a head rest of the character described, the combination of: a base comprising a U-shaped member having forwardly extending legs and vertically extensible posts extending upwardly from the intermediate portions of said legs; a rest hingedly supported at the upper ends of said posts so as to swing on a lateral axis, said

rest comprising a pair of side members joined by a hinge at their rear ends and having lateral swinging movement, there being lever members extending rearward from the rear portions of said side members; screw means connecting said lever members so as to swing said lever members on said hinge; and adjustment means connecting the rear portion of said base with said lever members, operative to swing said rest on said lateral axis.

2. In a head rest of the character described, the combination of: a base comprising a U-shaped member having forwardly extending legs and vertically extensible posts extending upwardly from the intermediate portions of said legs; a rest laterally slidably and hingedly supported at the upper ends of said posts so as to swing on a lateral axis, said rest comprising a pair of side members joined by a hinge at their rear ends and having lateral swinging movement, there being lever members extending rearward from the rear portions of said side members; screw means connecting said lever members so as to swing said lever members on said hinge; adjustment means connecting the rear portion of said base with said lever members, operative to swing said rest on said lateral axis; and means for locking at least one of said posts to a side member of said rest.

3. In a head rest of the character described, the combination of: a base comprising a U-shaped member having forwardly extending legs and vertically extensible posts extending upwardly from the intermediate portions of said legs, said posts having laterally extending openings at the upper ends thereof defining a lateral axis; a rest hingedly supported at the upper ends of said posts, said rest comprising a pair of side members joined by a hinge at their rear ends and having lateral swinging movement, there being lever members extending rearward from the rear portions of said side members, and there being means intermediate the ends of said side members supporting bars in positions extending through said openings at the upper ends of said posts and so as to slide a limited distance along said lateral axis; screw means connecting said lever members so as to swing said lever members on said hinge; adjustment means connecting the rear portion of said base with said lever members, operative to swing said rest on said lateral axis; and means carried by at least one of said posts to engage at least one of said side bars so as to prevent it from sliding along said lateral axis.

SAMUEL R. JONES.
